SOLUTION FEEDING DEVICE

Alfred N. Munn, Huntington Park, Calif.

Application February 14, 1939, Serial No. 256,393

6 Claims. (Cl. 210—39)

This invention relates generally to the treatment of liquids with various solutions either in circulating and water dispensing systems, such as plumbing installations, or relatively static liquid systems, such as water reservoirs.

An object of the invention is to provide a device structurally characterized by a simple, dependable and positively acting means which, in its association with the plumbing system of a building, as an example, automatically supplies a rust preventing or other beneficial solution in predetermined quantities to the system over a relatively long period of time, all without requiring any intermediate servicing or attention.

A further object of the invention is to provide a device of the above described character which embodies a sight feed for the solution so that the operation can be observed at any time.

Another object of the invention is to provide means by which gravity flow of solution into the water being treated is effected in an air-free circuit, including a solution receptacle from which the solution gravitates into and is displaced by water from the system, all in such manner as to insure positive treatment of the water with a predetermined amount of the solution.

Still another object of the invention is to provide means by which the supply of solution can be replenished with the utmost ease and dispatch in a manner positively preventing the entrance of air to interfere with the automatic flow of solution into the water system in the normal operation of the device, and without incurring loss of any solution remaining in the displacement water in the receptacle.

With these and other objects in view, the invention resides in the combinations, arrangements and functional relationships of elements as set forth in the following specification and particularly pointed out in the appended claims.

In the accompanying drawing—

Figure 1 is a view showing partly in elevation and partly in vertical section, one form of solution feeding device embodying this invention;

Figure 2 is a detail sectional view taken on the line 2—2 of Figure 1.

Referring specifically to the drawing, the invention, in its present embodiment, comprises a solution receptacle 10 in the form of a cylindrical container which can be rigidly supported from a water supply pipe 11 by clamping straps 12 and 13, or in any other suitable manner.

Connected to the receptacle 10 at the top 55

portion thereof is the horizontal branch 14 of a conduit 15 also including a vertical branch 16 connected to the horizontal branch by a T fitting 17 provided with a drain plug 18.

5 The vertical branch 16 is provided with a valve 19 and extends freely through an axial passage 20 in a head 21 of a separate chamber 22 defined by the head 21, a flange 23, and a transparent tube 24, the ends of which are sealed against ring gaskets 25 and 26 by bolts 27 and nuts 28 connecting the head and flange.

The vertical branch 16 is secured to the head 21 co-axially of its passage 20 by a gland nut 29; and the head is provided with a lateral inlet passage 30 communicating with the passage 20 and having connected thereto a second conduit 31 communicating with the receptacle 10 at the bottom portion thereof and provided with a valve 32.

15 The lower end of the vertical branch 16 is screwed into the bore 33 of the body of a valve 34, and one end of the body is screwed into the flange 23, so that the bore functions as a part of the conduit 15.

20 The other end of the bore 33 has screwed thereinto a nozzle 35 having a metering discharge orifice 36 placing the conduit 15 in communication with the water supply pipe 11 through the medium of a feed chamber 37 and a pipe 38 having a valve 39 and connected to the water supply pipe by a T fitting 40.

25 The feed chamber 37 is formed by a flange 41, a head 42 and a transparent tube 43, the ends of which are sealed against ring gaskets 44 and 45 by bolts 46 and nuts 47 connecting the flange and head. The other end of the body of the valve 34 is screwed into the flange 41 so as to secure the valve thereto; and the head 42 is provided with a filling plug 48 and with a lateral outlet passage 49 to which the pipe 38 is connected so that the latter co-acts with the passage 49 and with the feed chamber 37 to place the discharge orifice 36 of the conduit 15 in communication with the liquid line defined by the water supply pipe 11.

30 That portion of the conduit 15 which extends through the separating chamber is provided with ports 50 and with a baffle member or separator 51 in the form of a bell shaped hood fixed on the conduit, with the lower marginal edge of the separator disposed at the same level as the lowermost portion of the ports 50 for a purpose to be described in the operation of the invention, which is as follows:

35 The operation of supplying the receptacle 10

with a solution which is heavier than water and is for example of a nature to prevent rust and corrosion in the piping of the plumbing system consists of first removing the drain plug 18 and opening all valves 19, 32, 34 and 39, a suitable temporary hose connection being made to the T fitting 17 for the hose (not shown) to discharge into a suitable vessel. All air will now be expelled from every space in the device by water under pressure from the supply pipe 11 entering the device through the pipe 38. It is to be understood that the nozzle 35 has not as yet been applied to the device, as the nozzle would interfere with the free flow of water in filling and testing the device, and is thus removed each time the device is to be charged with solution.

As soon as water flows from the hose connected to the T fitting 17, the valve 39 is closed and the plug 18 replaced. The valve 39 can now be opened for a test to determine pressure tightness of all connections, following which the valve 39 is again closed.

The plug 18 is again removed and replaced by the drain hose, and the plug 48 is removed and a filler hose (not shown) connected to the head 42 in place of the plug.

With the valve 19 closed, a quantity of the solution, preferably about two-thirds of the capacity of the receptacle 10, is forced through the filler hose by a suitable hand pump or other means (not shown) and enters the bottom of the receptacle so as to force the water above from the receptacle through the branch 14 and the drain hose. By measuring the water discharged from the drain hose, the exact amount of solution supplied to the receptacle is determined.

The valve 34 is now closed, the filler and drain hoses disconnected, and the plug 18, nozzle 35, and plug 48 replaced, after which all closed valves are opened.

As the solution supplied to the receptacle 10 has a greater specific gravity than water, the solution will flow by gravity from the receptacle through the pipe 31, passages 30 and 20 into the separating chamber 22, and will pass underneath the separator 51 so as to enter the conduit 15 through the ports 50 and finally discharge in a slow fine stream from the orifice 36 of the nozzle 35. It will be noted that the bottom of the bore of the nozzle 35 is flat which tends to prevent foreign particles from clogging the orifice 36.

As the stream of solution enters the feed chamber 37 to a point near the bottom of same, the solution is mixed with water in the pipe 38 and finally carried through the system by water flowing in the supply pipe 11, all as shown by the full line arrows in Figure 1.

Concurrently with this feeding of the solution, the stream of solution discharging from the nozzle 35 is surrounded by water counterflowing from the supply pipe and upwardly through the conduit 15 into the top of the receptacle to displace solution as discharged from the bottom thereof, all as indicated by the broken line arrows in Figure 1. A relatively small amount of solution is carried along by this displacement water to the top of the receptacle, but settles to the bottom thereof so that the water is always on top of the heavier solution.

By the provision of the separator 51, water flowing upwardly in the conduit 15 is prevented from entering the chamber 22 and flowing into the bottom of the receptacle as the location of

the separator relative to the ports 50 enables the heavier incoming solution in the chamber 22 to act as a barrier to the counterflowing water. Furthermore, it will be noted that the water flowing upwardly around the stream of solution discharging from the nozzle 35 acts to dislodge any foreign particles which may accumulate on the flat bottom inside the nozzle, so as to insure that the orifice 36 will be maintained open.

The feed of solution is automatically proportioned to the flow of water in the water pipe 11, by utilizing the pressure drop in the system which naturally occurs upon opening any valve or faucet in the system. It is to be understood that the size of the orifice 36 is calculated to feed a predetermined amount of solution for the average volume of water used in a certain time.

When a pressure drop occurs in the system outside of the nozzle 35, there is a temporary unbalanced pressure condition which manifests itself by an increased feed of the solution from the nozzle to mix with the water flowing into the system. Immediately upon the restoration of the balance of pressure, the amount of solution discharged from the receptacle is replaced with water flowing thereinto as indicated by the broken line arrows.

When the invention is to be used for the feeding of a solution to an open tank or reservoir, a pipe (not shown) is substituted for the pipe 38 and attached to the inlet pipe of the tank or reservoir. In such an installation, the solution is fed by gravity alone.

What is claimed is:

1. In a system of the class described, a liquid line, a receptacle adapted to contain a solution the specific gravity of which is greater than that of the liquid with which it is to be mixed; means connected to the liquid line through which solution in the receptacle flows from the bottom portion thereof by gravity to mix with liquid in said line; means co-actable with the first means to enable liquid from the line to enter the top portion of the receptacle by displacing solution flowing therefrom; means by which the first means is utilized to effect the flow of displacement liquid therethrough to the top portion of the receptacle in a direction counter to the direction of solution flow through the first means from the bottom portion of the container; and means co-actable with the last means to prevent counterflowing liquid from entering the receptacle from the bottom portion thereof.

2. In a system of the class described, a liquid line, a receptacle adapted to contain a solution the specific gravity of which is greater than that of the liquid with which it is to be mixed; a feed chamber connected to the liquid line; a conduit communicating with the upper portion of the receptacle and having a solution discharge orifice opening to the feed chamber; a separating chamber; means placing said conduit in communication with the separating chamber; and a second conduit connecting the bottom portion of the receptacle with the separating chamber for the gravity flow of solution thereto from the bottom portion of the receptacle, and through the last means into the first said conduit so as to be discharged from said orifice into the feed chamber and thence into the liquid line.

3. In a system of the class described, a liquid line, a receptacle adapted to contain a solution the specific gravity of which is greater than that of the liquid with which it is to be mixed;

a feed chamber connected to the liquid line; a conduit communicating with the upper portion of the receptacle and having a solution discharge orifice opening to the feed chamber; a separating chamber; means placing said conduit in communication with the separating chamber; a second conduit connecting the bottom portion of the receptacle with the separating chamber for the gravity flow of solution thereto from the bottom portion of the receptacle, and through the last means into the first said conduit so as to be discharged from said orifice into the feed chamber and thence into the liquid line; and means by which liquid from the line counterflowing through the first said conduit to displace solution discharging from the receptacle is prevented from entering the latter through the second said conduit.

4. In a system of the class described, a liquid line, a receptacle adapted to contain a solution the specific gravity of which is greater than that of the liquid with which it is to be mixed; a feed chamber connected to the liquid line; a conduit communicating with the upper portion of the receptacle and having a solution discharge orifice opening to the feed chamber; a separating chamber through which said conduit extends, with the conduit having a port opening to the separating chamber; and a second conduit connecting the bottom portion of the receptacle with the separating chamber for the gravity flow of solution thereto from the bottom portion of the receptacle, and through said port into the first said conduit so as to be discharged from said orifice into the feed chamber and thence into the liquid line.

5. In a system of the class described, a liquid line, a receptacle adapted to contain a solution the specific gravity of which is greater than that of the liquid with which it is to be mixed; a feed

chamber connected to the liquid line; a conduit communicating with the upper portion of the receptacle and having a solution discharge orifice opening to the feed chamber; a separating chamber through which said conduit extends, with the conduit having a port opening to the separating chamber; a second conduit connecting the bottom portion of the receptacle with the separating chamber for the gravity flow of solution thereto from the bottom portion of the receptacle, and through said port into the first said conduit so as to be discharged from said orifice into the feed chamber and thence into the liquid line; and a baffle member mounted on the first conduit in a position to co-act with the port thereof in preventing counterflowing liquid entering the bottom portions of the receptacle from the first conduit through the port thereof.

6. In a system of the class described, a liquid line, a receptacle adapted to contain a solution the specific gravity of which is greater than that of the liquid with which it is to be mixed; a conduit communicating with the upper portion of the receptacle and having an orifice in communication with the liquid line; means defining a chamber in communication with the bottom portion of the receptacle, and through which a ported portion of said conduit extends for the gravity flow of solution from the bottom portion of the receptacle into the liquid line through the port, conduit and orifice, as liquid from the line counterflows through the conduit into the top portion of the receptacle to displace the discharged solution; and means in said chamber coactable with the port of the conduit, in preventing counterflowing liquid from entering the bottom portion of the receptacle via the port and chamber.
